PROCESS AND MACHINE FOR THREADING
THE NECKS OF TUBES

Edwin H. Barker, Moylan, Pa., assignor to A. H. Wirz, Inc., Chester, Pa., a corporation of Pennsylvania

Application December 31, 1930
Serial No. 505,892

17 Claims. (Cl. 113—44)

My invention relates to forming metallic objects by pressure and particularly to threading the necks of collapsible metallic tubes in which tooth paste, shaving cream or the like may be placed.

The main purpose of my invention is to form a metallic object by pressure of a resilient solid die against a rigid die.

A further purpose is to thread the neck of a tube by internal concurrent pressure.

A further purpose is to form threads on the neck of a tube by applying pressure to a die of rubber or the like, the die pressing the metal of the tube into threads in a rigid die to form threads on the neck of the tube.

A further purpose is to provide mechanism by which threads can be formed on the neck of a tube by manually placing the tube on a mandrel, placing a die about the tube on the mandrel, applying pressure to one end of the tube on the mandrel, and causing compression of a rubber die which is secured inside the mandrel and projects therefrom to form threads on the tube as a result of axial movement of a press.

A further purpose is to provide a pressure threading mechanism that is operated by a punch press or the like which comprises a mandrel for receiving a tube, and a cam-operated outer die adapted to engage and disengage the ends of the tube about the mandrel and cause pressure to be exerted against the end of the tube.

A further purpose is to thread the neck of a tube in a die, by presenting a tube on a mandrel to a die, locking the die to the tube and the mandrel by partial vertical movement of the press head, and continuing vertical movement of the press-head applying pressure to the end of the mandrel to form threads on the tube.

A further purpose is to provide a resiliently operated mandrel which presents a rubber extension to the interior of the neck of a tube.

A further purpose is to provide a two-part mandrel having one part movable and the other part stationary adapted to present a rubber sleeve to a tube for pressure threading.

A further purpose is to provide a larger interior neck portion of a tube by resilient expansion of the tube.

My invention relates both to the methods involved and to mechanism by which the methods can be carried out.

Further purposes will appear in the specification and in the claims.

I have preferred to illustrate one form only of my invention with a minor modification, showing

it in application to a press, selecting a form that is practical and efficient in operation and which well illustrates the principles involved.

Figure 1 is a front elevation of a press with my pressure threading device in place on the press and with a tube in position for threading.

Figure 1a is an enlarged section through the dies seen in Figure 1.

Figure 2 is a vertical section taken on the line 2—2 of Figure 1.

Figure 3 is an enlarged vertical section taken on the line 3—3 of Figure 1.

Figure 4 is a vertical section taken on the line 4—4 of Figure 3.

Figure 5 is a vertical section similar to Figure 4, but with the parts in a different position.

Figure 6 is a bottom plan view of the die locking device, showing in closed position means I employ, corresponding to the line 6—6 of Figure 4.

Figure 7 is a view similar to Figure 6 but showing the locking device in open position.

Figure 8 is a fragmentary sectional elevation of a tube before the threads have been pressed on the neck thereof.

Figures 9, 10 and 11 are enlarged detail views of a portion of the structure seen in Figure 4 showing different steps in the formation of a thread in the neck of a tube.

Figure 12 is a sectional plan view taken on the line 12—12 of Figure 11.

Figure 13 is a fragmentary sectional elevation of a tube after the threads have been pressed thereon.

Figure 14 is a fragmentary elevation similar to a portion of Figure 1, but showing a modification of the arrangement of the structure.

Figure 15 is a vertical section taken on the line 15—15 of Figure 14.

Figure 16 is a vertical section similar to Figure 13 showing a tool in cutting position at the end of the tube.

Figure 17 is a fragmentary sectional elevation showing a modification of the die arrangement.

Describing in illustration but not in limitation and referring to the drawings:

Collapsible metallic tubes are extruded from blanks which are much thicker than the breast or shoulder of a tube, but otherwise of about the same diameter and shape.

The tube is extruded instantaneously to include a neck or nipple having a closed discharge end.

In the past threads have been cut or rolled in a thick neck resulting in waste of metal and also requiring extreme accuracy in positioning the cutting tool, due to the very delicate construction.

of the tube walls; and threads have been rolled into a thin neck from the inside.

In my U. S. Patent No. 1,733,712, dated October 29, 1929, I have shown a pressure-threading device for the neck of collapsible tubes in which a roller was employed to press the thin walls of the tube into threads in the die and this has been used to a considerable extent.

The present method and apparatus offer some advantages over this threading invention, particularly in speed, and do not require the same care in accuracy of adjustment as does the patented form.

Almost all of these tubes are made of pure tin. In some cases, where the content is not capable of contamination, lead alloys and even pure lead are used. The thin tube and neck walls are easily injured and require corresponding care in threading the neck.

I have found it very desirable to form the neck extension of the tube with walls of somewhat greater thickness than the tube, forming the discharge end of the neck closed and initially of thickened material which is subsequently trimmed.

With the thin wall neck construction I find that by applying pressure outwardly to the walls of the neck against a restraining threaded die it is possible to form a very accurate thread in the neck of the tube.

In Figure 1 I have shown my invention as applied in a punch press, which is the simplest form I know in which to apply it commercially with speed and which, for present purposes, I therefore view as a largely diagrammatic illustration of the invention, notwithstanding that a press of this character has been used by me in practical operation to thread the tubes.

The vital parts of the invention are represented in relatively enlarged section in Figure 1a, in which I show the tube 20, shoulder 21, discharge nipple or neck 22 and closed end 23 in position with the nipple unthreaded and located between transversely separable threaded outer die members 24 and 25. Within the tube is a mandrel 26 which supports the top of the tube and whose tapered end 27 supports the shoulder of the tube against the dished faces 28 and 29 of the outer die. Within the mandrel moves a plunger 30 by which a resilient material 31 is longitudinally compressed to cause it to expand radially against the interior of the discharge neck to swell the discharge neck outwardly into engagement with the interior threads of the outer die.

The tube to be threaded is placed upon the mandrel during the time that the plunger and the male die carried with it are retracted at least partly within the mandrel as seen in Figure 9. This is therefore considered as the feeding position of the plunger 30 and the male die 31. The plunger and male die are movable from the feeding position of Figure 9 to the positions of Figure 10 and Figure 11. The pressing begins with the position in Figure 10 and continues to complete the threading operation as seen in Figure 11. Either of these and any range between the two may therefore be considered as the pressing position or positions of the plunger and male die.

Because the resilient material performs die functions I have preferred to call it a die. The end of the discharge nozzle is supported by an anvil or stop 32.

It will be obvious that the essential parts comprise the outer die members, a stop to take the

thrust of the inner die, the inner die itself, and means for compressing and thereby expanding the inner die, without regard to whether the inner die be hollow or solid and without regard to the material of the inner die, except that it must be capable of the function described.

For convenience of holding, and because it can be purchased to advantage in that form without necessity for special manufacture, the inner die 31 is shown in the form of a tube which can be mounted upon the serrated nose 33 of the plunger 30. It is, of course, necessary that the tube be properly mounted and supported, that the plunger be guided and that the inner die be externally supported back of its effective operating point, but these features are rather cooperative to apply the inner die to its work than directly effective to form the thread. My invention contemplates the use of these additional aids in applying the interior expanding die to its work.

Because of the requirement of the statute I have shown one mechanism for properly resiliently supporting the parts, such as are shown in Figure 1a, for example, and for pressing and guiding them to their duty. These form the parts of a punch press 34 shown in Figures 1 and 2, and in less detail in various other figures.

In the press the base plate 35 of the mandrel support 36 is mounted upon the press bed 37.

The mandrel support 36 from bed 37 comprises upward extensions 38 and 39 which form bearing support for a pin 40 about which a rocker arm 41 is pivoted.

Because resilient support for the mandrel is highly necessary I supply this by a convenient form movable on the pin to permit access for loading. The rocker arm 41 is reduced at its upper end 42 and forms a shoulder 43 on which is mounted a bottom spring-supporting plate 44. An upper pin-carrying plate 45 has secured thereto in a number of guide pins 46 that project downwardly and through openings 47 in the lower plate 44.

Springs 48 surround the pins 46 between the upper and lower plates 45 and 44 to allow resilience between the upper and lower plates.

The mandrel 26 is placed on the upper plate 45 and is free to move vertically a short distance. The mandrel is centered by a spindle 49 enlarged at 50 to fit an opening 51 in the rocker arm 41 and secured thereto by a set-screw 52.

The spindle 49 is reduced in diameter at 53 to project through an opening 54 in the upper plate 45 into an enlarged hollow portion 55 of the mandrel 26. The spindle 49 is further reduced in diameter at 56 to fit a corresponding reduced opening 57 in the mandrel.

At approximately the upper end of the opening 57 the mandrel stub 58 is threaded internally at 59 to receive a threaded end 60 of the mandrel end 61 tapered at its outer end 27 to conform to the shape of the breast or shoulder of a tube. The mandrel end is bored at 62 and counterbored at 63, the bore 62 to receive the plunger 30 and the counterbore 63 to receive the enlarged head 64 of the plunger. The threading at 58 permits ready separation of the parts so that the plunger 30 carrying the male die can be removed and a new male die may be replaced upon the serrated nose 33 of the plunger.

A spring 65 is placed about the reduced plunger 30, between the head 64 and a shoulder 66 formed by the end of the counterbore 63.

The operation of the parts shown in Figure 1a has already been explained.

To a slide 67 which is fastened on the head 68 of the punch press I mount die clamping mechanism in the form of a base 69 which may conveniently serve as stop 32, to which are pivoted at 70 the split die members 24 and 25.

At their outer ends 71 the die members are recessed at 72 and 73. In the recessed portions a cam 74 is pivoted to a cam shaft 75, the outer surfaces 76 and 77 of the cam 74 cooperating with the ends 71 of the die members to move them into and out of engagement with the neck of the tube. The inward movement of the die members is aided by springs 78 fastened to and between the die members.

15 A guide and stop pin 79 is placed on the base to assure positive registry of the die members in closed position.

The cam shaft 75 has pivoted thereon a closing member 80 provided with gripping fingers 81 and 82 that engage the outer ends of pins 83 and 84 to clamp the dies about the neck of the tube.

An actuating lever 85 is pivoted to the cam shaft 75 and carries a roller 86 at the end of an arm 87. The roller 86 operates in a cam slot 88 in a plate fastened to any stationary part of the press to open and close the die members.

As seen in Figure 2 the mandrel and its support can be swung on its pivot against the action of a spring 89, one end of which is fastened to the extended arm 90 of the rocker arm 41 and the opposite end of which is fastened to the bed plate of the press.

Swinging of the arm and mandrel allows the operator to place a tube upon the mandrel, after which the mandrel is allowed to move back in line with the head of the press bringing the tube in line with the die on the head of the press.

At this point of operation, the head of the press starts to move down into the position seen in Figure 5. The clamping die assumes the position illustrated in Figure 7.

Further downward movement of the press causes the head to move down further and at the same time the arm carrying the roller is moved in the cam slot secured to the stationary structure of the press. This causes the die members to tighten about the neck of the tube, the locking members of the die assuming a position corresponding to that shown in Figure 6.

Final movement of the press head causes the rubber die to expand and force the thin metal of the neck of the tube into the threads formed in the die, completing the threading operation.

55 It will be noted that, as the press operates the resilience of the springs 48 causes the mandrel to move downwardly some distance before the rubber sleeve is exposed any considerable distance outside the end of the mandrel in position to be expanded against the tube nipple.

When the mandrel is pressed downwardly as before mentioned the enlarged head 64 of the plunger will engage the end of the reduced portion 56 of the lower spindle 49 which will force 65 the plunger outwardly along with the rubber carried by it.

The end or outer closing portion 89 of the tube is of somewhat thicker material than that of the side walls as explained and as seen in Figures 8, 9, 10 and 12, in order that its stiffening effect may additionally support the discharge tube or nipple during formation of the thread. It is then cut. A cutter for this face is shown at 90 in Figure 16. This cutting should be done 75 at high speed. The cutter 90 is preferably formed

with a spiral face 91 about an open center 92. The extension 93 of the spiral face throughout a considerable part of the circumference of the hollow tool is found to be quite advantageous in preventing objectionable curling of chips cut and keeping the chips from interfering with the operation.

In Figures 14 and 15 a modification is shown in which the supporting mandrel is secured to a slide in the head of a punch press and the threading die is fastened to the bed plate.

The parts are identical to that shown in the previous figures except that the mandrel support does not swing and spring fingers 94 are used to hold the tube in place about the mandrel. Another variation in the construction is that the cam that moves the die-operating arm is carried by the movable head of the press. I have accordingly given the parts the same reference numerals.

It will be evident that my broad invention, which comprises forming metallic objects between a rigid die and a solid resilient die, as well as the specific application of my invention to the threading of collapsible metal tubes, is subject to numerous variations, which, however, though not as advantageous as those shown in my preferred form, would be satisfactory or possibly even desirable in certain cases.

It will be evident that the tube or other object which is being formed need not be fluid-tight. This has a distinct advantage over methods employing fluid pressure in forming, where fluid-tightness is essential. In Figure 17 I show the end of the tube open at 95. This open-end tube could be used in any of the forms of my invention, but it is less desirable than the closed-end tube, because the metal closing the end likewise stiffens the end of the tube and is an extra security against distortion. I therefore prefer to 115 cut off the end of the tube subsequent to the threading operation, although the end of the tube could be cut off before threading as indicated in Figure 17.

Provided one of the dies is of resilient solid 120 material, it is not essential that the resilient die be male, although this is preferable because, where a rigid male die is used, it cannot be directly withdrawn, but must be unscrewed from the tube, or else the male die must be made in 125 several separable parts. Subject to these objections, a resilient female die and rigid male die may be employed. In Figure 17 I indicate a resilient female die 96 formed in the shape of a ring, supported by a collar 97 and tightened by 130 pressure of a tapered sleeve-like extension 98 of a plunger 99. The male die 100 is in this case rigid, so that the tube walls may be forced by the resilient female die radially inward into the male die.

Of course the contour of the male and female dies will depend upon the shape which is to be produced and the character of the work upon which the dies operate. My invention is not restricted to threading of collapsible metal tubes, 140 but is applicable to the metal shaping and stamping arts generally and may be applied to shape objects at the same time that other operations, as for example, cutting of metal, are being performed.

While the form which I show is primarily intended for a vertical press and for a single mandrel press, it will of course be understood that my invention is equally applicable to horizontal mandrels and to machines having a plurality of man- 150

mandrels, whether operation be upon several mandrels at one time or successively upon different mandrels and whatever the means for progressing the mandrels and for charging and discharging the work to and from the mandrels.

The character of charging, discharging and conveying means used are matters of convenience only, relating rather to the speed of operation of the press than to the method of forming the metal, and I of course intend my invention to be applicable in any setting, whether automatic or manual.

The addition of special attachments to the press or to the mandrel, such as, for example, blow-off means for removing the tube from the mandrel, whether employing compressed air or otherwise, is not important to the present invention and is rather likely to complicate the drawings and description and therefore has been omitted from the illustration, but it will be understood that blow-off or other removal means may readily be applied without altering the principles disclosed.

For convenience in description in the claims, my resilient material is referred to as solid to distinguish from liquid or gases without intending to indicate that it need be without a central aperture—and in fact I prefer a central aperture—nor to suggest that it need be free from porosity.

In view of my invention and disclosure variations and modifications to meet individual whims or particular need will doubtless become evident to others skilled in the art, to obtain part or all of the benefit of my invention without copying the structure shown, and I, therefore, claim all such in so far as they fall within the reasonable spirit and scope of my invention.

Having thus described my invention, what I claim as new and desire to secure by Letters Patent is:—

1. In a device for forming tubular metal objects, a female die, a cooperating male die, one surrounding the other, one of which dies is rigid and the other of which is a resilient solid, and means for moving one of the dies lengthwise of the tubular objects with respect to the other to clear the dies in one direction of movement and to insert the one die within the other and expand the resilient solid material by engagement with a fixed surface.

2. In a device for threading the end of a collapsible metal tube, a rigid threaded female die adapted to surround the end of the tube, a rubber male die adapted to lie within the end of the tube, a plunger upon which the rubber die is mounted, means for moving the plunger lengthwise of the tube to insert the male die within the tube end and to expand the male die and the tube wall outward against the female die, and a stop for the end of the tube.

3. In a device for forming tubular metal objects, a support for the tubular objects, a male die movable longitudinally therein and a split female die therefor comprising pivoted die halves pivoted at one end each, a stop limiting the movement of the halves toward each other to their intended operating positions, spring means for drawing the dies together, and combined cam means for locking the dies together with one movement of the cam and for opening them with an opposite movement thereof.

4. In a device for forming tubular metal objects, cooperating male and female dies, the female die comprising pivoted die members spring-

drawn toward each other, and cam means for locking the die parts with one direction of movement and for separating the die parts with an opposite direction of movement.

5. In a device for threading the end of a collapsible metal tube, a rigid threaded female die divided into segments, means for separating the segments, means for moving the female die with respect to the tube to a position about the end of the tube while the segments are separated, means for closing the segments about the end of the tube, means for locking the segments in closed position, a resilient solid male die cooperating with the female die and adapted to lie within the end of the tube, and means for expanding the male die and the tube wall outward against the female die. 80

6. In a device for threading the end of a collapsible metal tube, a rigid threaded female die adapted to surround the end of the tube, a resilient solid male die adapted to lie within the end of the tube, a mandrel supporting the male die and within which the male die enters when not in use, a plunger movable with respect to the mandrel in an opening through the mandrel, carrying the male die and axially compressing the male die in one position, and means for forcing the plunger against the male die to expand the male die and the tube wall against the female die. 85

7. In a device for threading the end of a collapsible tube, a rigid threaded female die adapted to surround the end of the tube, a resilient solid male die adapted to lie within the end of the tube, a mandrel supporting the male die, a plunger movable with respect to the mandrel in an opening through the mandrel and engaging the male die, means for applying pressure to the plunger to expand the male die and the tube wall against the female die, and means permitting ready removal of the plunger from the mandrel for replacement of the male die. 90

8. In a device for threading the end of a collapsible metal tube, a rigid threaded female die adapted to surround the end of the tube, a resilient solid male die adapted to lie within the end of the tube, a mandrel supporting the male die, a plunger movable with respect to the mandrel in an opening through the mandrel and engaging the male die, a spring resiliently urging the plunger away from the male die, and means for forcing the plunger toward the male die against the action of the spring to expand the male die and the tube wall against the female die. 100

9. In a device for threading the end of a collapsible metal tube, a rigid threaded female die, a hollow annular resilient male die of solid material, and a plunger having an end extending into the hollow interior of the male die by which the plunger and one end of the male die are rigidly attached, the plunger being movable with respect to the remainder of the male die to axially compress the male die and thus radially expand it against the tube wall. 110

10. In a device for threading the end of a collapsible metal tube, a rigid threaded female die adapted to surround the end of the tube, a hollow annular male die adapted to lie within the end of the tube, a plunger having an annularly ribbed end movable with respect to the end of the male die, extending within and pressing against the male die, and pressure means for forcing the plunger against the male die to expand the male die and the tube wall against the female die. 120

11. In a device for threading the end of a col- 130

51. Collapsible metal tube, cooperating male and female dies, one of which is threaded and rigid and the other of which is a resilient solid, a mandrel supporting the male die and movable from a feeding position to a pressing position, and pressure means operable when the mandrel is in pressing position for forcing the resilient die against the tube wall backed up by the rigid die. 80
52. In a device for threading the end of a collapsible metal tube, cooperating male and female dies, one of which is threaded and rigid and the other of which is a resilient solid, a mandrel supporting the male die and movable from a feeding position to a pressing position, means for automatically moving the mandrel from its feeding to its pressing position, and pressure means for forcing the resilient die against the tube wall backed up by the rigid die when the mandrel is in pressing position. 85
53. In collapsible tube working machinery, a female die divided into a plurality of segments, a male die cooperating with the female die and consisting of a resilient solid, means for applying pressure to the male die, and means for locking together the segments of the female die responsive to the means for applying pressure to the male die. 90
54. In a device for threading the end of a collapsible metal tube, a rigid threaded female die divided into a plurality of segments and adapted to surround the end of the tube, a resilient male die of solid material adapted to lie within the end of the tube, means for moving the female die axially with respect to the tube, means for applying pressure to the male die, means controlled by the pressure means for maintaining the segments of the female die separated when the female die moves axially of the tube, and means controlled by the pressure means for locking the female die segments together when pressure is applied to the male die. 95
55. In a device for threading collapsible tubes, a female die having the outline of threads upon its interior surface, a male die cooperating with the female die and comprising a rigid plunger and a tubular terminal of solid material secured to the outside of the plunger to move forward and backward, a mandrel laterally supporting the male die, means for moving the male die longitudinally with respect to the mandrel and a cushion support for the mandrel. 100
56. The method of threading the neck of a collapsible tube, which consists in supporting the outside of the shoulder of the tube, in applying pressure to the inside of the shoulder to hold the tube, in laterally supporting the body of the tube, in surrounding the neck of the tube by a threaded contour to be given to the neck, in introducing rubber into the inside of the neck and in applying pressure to the rubber to radially expand the neck and form threads on it. 105
57. The method of threading the neck of a collapsible tube, which consists in supporting the outside of the shoulder of the tube, in applying pressure to the inside of the shoulder to hold the tube, in laterally supporting the body of the tube, in surrounding the neck of the tube by a threaded contour to be given to the neck, in introducing rubber into the inside of the neck and in forcing the rubber against the end of the nipple of the tube to radially expand the rubber and form threads on the neck. 110
